UNITED STATES PATENT OFFICE.

ARVID W. ECKBERG AND CARL STOHLBERG, OF JAMESTOWN, NEW YORK.

SHEET-METAL WINDOW.

1,074,702.

Specification of Letters Patent.

Patented Oct. 7, 1913.

Original application filed September 19, 1911, Serial No. 650,209. Divided and this application filed December 9, 1911. Serial No. 664,703.

To all whom it may concern:

Be it known that we, ARVID W. ECKBERG and CARL STOHLBERG, citizens of the United States, residing at Jamestown, in the county 5 of Chautauqua and State of New York, have invented certain new and useful Improvements in Sheet-Metal Windows, of which the following, taken in connection with the accompanying drawings, is a specification.

10 The invention relates to sheet metal window sash construction and the object of our improvement is to provide a strong and durable tubular sash construction having no loose stops on the window frame or sash 15 and permitting easy access to the interior of the tubular stiles and cross rails of the window sash; and the invention consists in the construction and arrangement of the parts as shown in this specification and the 20 accompanying drawings and pointed out in the claims.

In the drawings, Figure 1 is an elevation of a window frame with the sash therein. Fig. 2 is a sectional view of the sash and 25 window frame at line X X in Fig. 1, showing the construction of the frame and sash stile and the pivotal attachment between the two. Fig. 3 is a sectional view of the montant at line Y Y in Fig. 1 showing its construction. Fig. 4 is a lengthwise sectional view of the two sashes at line Z Z and a portion of the cap and sill of the window frame, portions of the glass being broken away.

35 Like numerals of reference refer to corresponding parts in the several views.

The numeral 10 designates a window frame which is preferably made of two pieces of sheet metal joined; as shown in 40 Fig. 2, so as to provide easy attachment to the surrounding wall. The face of the jamb is provided with parallel spaced grooves 11 in the track of the window sashes 12.

45 The stiles 13 and cross rails 19 and 20 of the window sashes are each preferably made of one piece of sheet metal in the tubular form and having a lengthwise groove 14 on the inner edge for the glass 15. Sufficient 50 space 16 is provided around the edge of the glass 15 for suitable packing.

The outer edges of the sash stiles 13 are provided with a lengthwise groove 17, the

edges of the sheet metal being bent inwardly and toward one another to form the groove, 55 but the edges are preferably a spaced distance apart to provide easy access to the interior of the stile and also because it is unnecessary for the strength of the sash that the edges should be joined. The spaced 60 distance between the inturned edges of the sheet metal in the groove 17 permits the painting or otherwise coating of the inside of the tubular stiles and cross rails and also prevents the condensation of moisture within 65 said tubular stiles and cross rails since the atmosphere is permitted to enter the tubular stiles and cross rails through this opening. The condensation of moisture within the hollow sheet metal construction 70 is one of its weaknesses since it easily starts rust and the disintegration of the metal. The tubular stiles and cross rails are joined at the corners preferably by welding since this gives a rigid construction without 75 visible joints.

The groove 17 receives therein the lengthwise channel strip 18, which channel strip 18 extends into the groove 11 on the jamb. The outer face of the sash stile 13 is made 80 to fit closely upon the face of the jamb and the groove 11 has sufficient depth to entirely receive the channel strip 18 so that when the strip 18 is moved into the channel 11 the sash 12 may be turned pivotally within 85 the oppositely facing jambs of the frame 10.

The top cross rail 20 of the upper sash and the bottom cross rail 19 of the lower sash are preferably made with a continuance 90 of the groove 17 to receive therein a projection 17' on the window sill 19' and a similar projection on the cap 20' of the frame 10, thereby forming a close joint between the upper and lower sashes and the sill 19' and cap 20'.

In order to insert the glass 15 in the upper and lower sashes the meeting rails of the sashes are each formed in two tubular parts 21 and 22, each of which form about one-third of the cross rail so that the two 100 parts may be placed a special distance apart to receive the glass 15 therebetween, as shown in Fig. 4. The tubular parts 21 and 22 of the meeting rails are constructed precisely the same in the upper and lower 105 sashes except that they are turned oppo-

sitely so that one forms the top cross rail of the lower sash and the other forms the bottom rail of the upper sash and the two interlap as hereinafter described.

5 A lengthwise projection 23 is provided on the outer edge of tubular part 21. The sheet metal inner side of part 22 is continued in an angular lengthwise flange 24 and the cap piece 25 is provided with a lengthwise 10 curved flange on the edge to fit over projection 23 and an angular return bend flange on the other edge to engage over flange 24 so that the two return bend flanges of the oppositely placed meeting rails interlap and 15 fit closely against one another, thereby closing the space between the two rails and holding the rails firmly together when the sash are in the closed position.

It is apparent that the glass 15 may be inserted through the slot between the two parts 21 and 22 before the cap 25 is slipped or sprung into place, and that after the said cap is in place it forms a continuation of the groove 14 and the glass may be cemented or 20 otherwise held in place in the sash within said groove, and also that the cap 25 may be easily removed for the replacing of the glass when broken. The part 21 is provided with an opening 30 and the part 22 with an opening 31 which admit to the interior of these parts for coating and prevent condensation as hereinbefore described. The tubular openings in parts 21 and 22 connect into the stiles 18 and crossbar, so that a continuous 25 opening is provided around the entire sash. This provides a simple and convenient sheet metal construction of which all the parts may be drawn in the regular molding drawing machines.

30 40 When a montant 26 is desired in the sash it is preferably formed of two channel strips 27 turned back to back with the channels facing oppositely, and cap strips 28 are then slipped over both the outer edges of the 45 channel strips 27, thereby forming a strong construction at low cost and one which provides the two outwardly facing grooves 29 for the glass 15.

By this construction the sash 12 are free 50 to slide up and down in the window frame 10, the channel pieces 18 sliding easily and forming a guide within the grooves 11 when the sash are free from one another or from the sill 19' or cap 20' of the frame, the sashes 55 may be turned pivotally upon the pivot bolt 32, the construction of which pivot bolt is fully described and claimed in the divisional application hereinbefore mentioned.

The window sill 19' is cut under and 60 drops away from the sash rail, as shown at 23 in Fig. 4, so that the drip from the outside of the window will always run away and cannot flow back through the joint between the under edge of the sash rail and the 65 lengthwise projection 17' on the sill 19'.

Should the lower cross rail 19 or the top cross rail 20 for any reason wish to be closed, a strip 34 may be spot welded on the inner side of the same, as shown in Fig. 4.

This arrangement permits a window frame construction having no loose stops or other pieces to get out of order. The window sash are free to be pivotally turned for cleaning or for ventilation, or may slide up and down in the window frame the same as 70 a common non-pivotally mounted sash.

We claim as new:—

1. In a sheet metal window, an upper and a lower sash each having a cross rail formed of two tubular parts, each cross rail having the outer side of its outer tubular part at the top thereof curved outwardly to form a projection, the other tubular part having its inner side spaced from the inner side of the other said tubular part to form a glass receiving space, the outer side of said second named tubular part being extended outwardly and then inwardly to form a flange which is spaced from the outer side of the second named tubular part, and a cap which has one side engaged over said projection and has its opposite side formed of U-shape in cross-section to receive the flange of the second named tubular part, the U-shaped sides of the caps when the cross rails are in 85 meeting position being engaged with each other and with the adjacent outer sides of the second named tubular parts of the cross rails.

2. In a sheet metal window, an upper and a lower sash each having a two-part cross rail, each cross rail having the outer side of its outer part extended outwardly and inwardly to form a flange which is spaced from the inner side of the cross rail, and a 100 cap engaged over said two parts of each of the cross-rails, said caps each having one side thereof formed of U-shape in cross section so as to receive said flanges in the space between the legs of the U-shaped parts, the adjacent legs of the U-shaped parts contacting when the sashes are closed and the other legs of the U-shaped parts contacting with the adjacent outer sides of the outer parts of the cross rails.

3. In a sheet metal window, an upper and a lower sash each having a two-part cross rail, and a cap for connecting the two parts of each cross rail, each cap having one side thereof spaced from the adjacent side of the cross rail, the said sides of the caps on their inner faces contacting when the sashes are closed and having their outer faces engaging said adjacent sides of the cross rails.

4. A sheet metal window sash having a lengthwise groove for the window glass on its inner edges, one side of said sash having a slot through the sash side to receive said window glass, projections on the outer sides of said slotted sash side, a cap having 115

flanged edges to engage over said projections and close said slot, the other three sash sides having lengthwise grooves in their outer edges with openings lengthwise in the bottom of said grooves admitting to the interior of the tubular sash sides, substantially as and for the purpose specified.

In testimony whereof we affix our signatures in the presence of two witnesses.

ARVID W. ECKBERG.
CARL STOHLBERG.
